UNITED STATES PATENT OFFICE.

GEORGE HOLT FRASER, OF NEW YORK, N. Y.

SEPARATOR.

1,165,865.

Specification of Letters Patent. Patented Dec. 28, 1915.

Application filed December 29, 1910, Serial No. 599,913. Renewed March 30, 1915. Serial No. 18,128.

To all whom it may concern:

Be it known that I, GEORGE HOLT FRASER, a citizen of the United States, residing in the borough of Brooklyn, in the county of

5 Kings, in the city and State of New York, United States of America, have invented certain new and useful Improvements in Separators, of which the following is a specification.

10 This invention relates to devices for separating, sizing, bolting, classifying, treating or collecting, materials by utilizing a fluid current, and aims to provide certain improvements therein.

15 Heretofore it has been common to distribute material within a feed chamber in which air currents act to draw the fine material into an outer casing, the fines settling in the outer casing and the air returning to the feed chamber, the coarse material falling through the air currents in the feed chamber and discharging from the bottom of the latter.

20 My invention provides improvements especially applicable to devices of this general character, and in its preferred form it utilizes a non-rotary feed tube and an initial distributer, in conjunction with a plurality of superposed annular distributers successively receiving the material, an annular exhaust chamber for each distributer, a blower for each distributer, an annular discharge passage for the combined exhaust of the several blowers, an auxiliary blower for speeding the current through said passage, a centrifugal separator for the dust laden current, and a plurality of settling chambers successively receiving the return current and classifying the material in suspension therein, in a reverse return passage for each settling chamber, means for separately withdrawing the different products, means for adjusting the currents for the respective distributers, and means for controlling the main current.

25 My invention also includes means for differentially driving the distributers and blowers, means for adjusting the non-rotary feed spout, improved bearings and bearing dispositions, improved damper arrangements, and various features of improvement in construction, arrangement and details, all of which will be hereinafter more fully set forth.

30 In the accompanying drawings, which show certain adaptations of my invention, Figure 1 is a vertical axial section showing the preferred form of my invention; Fig. 2

is a similar section showing a simpler form thereof, Fig. 3 is a similar section showing another form thereof, and Fig. 4 is a similar section showing another form.

35 Referring to the drawings, A indicates a casing, B the driving mechanism, C the feed hopper, D the distributer, E a chamber, F a blower, G the dust chamber, H the return passage, I the coarse outlet, and J the fine outlet. These may be of any usual or suitable construction and arrangement capable of distributing the feed, creating the necessary current, and collecting and discharging the products.

40 Referring to Fig. 1, I will now describe in detail the preferred form of my invention in the adaptation therein illustrated.

45 The casing A has a cylindrical body a and tapering or conical top and bottom, made in sections, preferably halves, braced and flanged, and adapted to be bolted to the adjoining circumferential sections, and it has as many vertical sections as are desired to 50 give the requisite height, two being shown. These sections are shown as straight and connected by bars b which tend to preserve the cylindrical form of the body and support the internal parts in position.

55 The upper part of the casing consists of a head c which is tapered in the form of a truncated cone and has an annular top d, and a central cavity or depressed portion e. The lower part of the casing consists of a 60 conical bottom f, suspended from the top body a. The body a is suspended from the top d, and the latter is suspended from the bearing frame g.

65 The driving mechanism shown consists of a driving shaft h carrying fast and loose pulleys i, and geared to the driven parts by bevel gears. This shaft is mounted in bearings in the frame g, which frame is shown as crossing the machine and supported by timbers at each side thereof, and the entire device as shown is suspended from the frame, which has one face coinciding with the diametric parting of the body.

70 The hopper C is preferably a stationary hopper, adapted to turn in any direction to connect with any source of feed, and preferably having a scalper and a tailing chute, and a screw threaded discharge outlet.

75 The feeder is preferably a non-rotary feed pipe J which is preferably vertically adjustable, as by screwing into the hopper outlet, and which leads into the casing and discharges onto a distributer K therein, the

speed of feed being determined by vertical adjustment of the pipe, or of the distributor, or of both, as desired.

- The distributor is preferably a rotary member, and preferably comprises the disk K and one or more successive distributors, as the rings L and M, which are carried by and revolve with the disk K in the construction shown. Opposite the disk K there is located a baffle ring k receiving the discharge therefrom and deflecting it downwardly toward the ring L, opposite which there is another similar baffle ring l, receiving discharge from the ring L and directing it down onto the ring M, opposite which there is another baffle ring m deflecting the material downwardly toward the return cone O. Opposite each baffle ring is an annular exhaust passage. These are lettered P Q and R respectively, and above these passages the blower F is provided with a series of blades p exhausting from the passage P, q exhausting from the passage Q, and r exhausting from the passage R. These blades are preferably tilting vertical blades, adapted to be driven in either direction, and are proportioned in number and size according to the current desired at the respective passages. The blower blades of each series are separated from those of the next series by rings s, which constitute essentially the top and bottom wall of each exhaust passage, so that each passage is practically isolated from the other passages by the walls of the distributors and the blower rings. Collectors n and o converge the material on rings L and M.

The blowers all preferably discharge into the exhaust chamber T, which tapers downwardly and outwardly and directs their combined discharge into the annular return passage U, through which it passes to the dust chamber G.

Swinging blades t are hung on the blower F and capable of inclining in either direction to give a downward acceleration to the current and aid in driving it through the passage U, and whirling blades u preferably are provided on the blower F for whirling the current while in the annular passage U, thus generating sufficient centrifugal action to aid in separating the dust by centrifugal force, so that by the time the current escapes from the passage U the heavier dust may be close to the outer wall, from which it will slide into the chamber G, and the inner air will be correspondingly cleaned.

As the air discharges from the passage U into the settling chamber G the returning air is drawn from it by an annular intake V, of greater superficial area than that of the passage U and immediately adjacent thereto, so that the downward motion of the dust in the discharge from the passage U may have opportunity to throw out much dust centrifu-

gally within the chamber G as the air current reverses to reach the return V. The air in the chamber G cleans itself by the process of settling, and by momentum and precipitation, before escaping through the return V, the area of which relative to the passage U is sufficiently great to so diminish the speed of flow of the return current for the air to free itself of floating particles.

A baffle ring v is preferably disposed above the chamber G to intercept the air as it whirls inwardly and to direct it toward the adjacent cone and meet upward currents there, and a regulating ring or damper W is preferably vertically adjustable within the passage V to control the air of the return and thus regulate its current speed. An annular suspended wall w constitutes the partition between the passages U and V and serves as the outer wall of the return passage H. The cone X constitutes the inner wall of this passage as well as the inner wall of the succeeding settling chamber O', and has an outlet x.

The air current flowing through the inlet of the return passage V, swings inwardly past the damper W and upwardly over the top edge of the cone X, and then flows eventually through the passage H to the center of the chamber O', from whence it may continue to the distributors, between which it may again be drawn through the suction passages by the blowers. In reaching these passages it must traverse the descending shower of material falling from each distributor to the next, composed of coarse and fine material, from which, as the current passes through, particles fine enough to be floated by it will be carried outward and upward through the blowers, while coarser material will continue over the distributors to the return cone O and be dropped from the latter into the bottom of the tailings cone S.

Adjustment or regulation of the current as to the different distributors may be obtained by differentiating the blowers, or otherwise, but is preferably effected from within the chamber E, as by the damper Y controlling the passage y beneath the disk K, the damper Z controlling the passage z beneath the distributor L, and the damper A' controlling the inlet a' beneath the distributor M.

Inclined annular walls b' are preferably attached beneath each distributor, and preferably carry blades c' which act as blowers to aid in accelerating the current beneath the distributors.

The dampers Y, Z and A' are independently adjustable from below in any suitable manner, as by the rod d' and pipes e' and f' respectively.

When independent speeds of the distributors and the blowers are desired the distributors are carried by and driven from a

tubular head B', which is suitably spaced above them to permit the necessary passage for material between the disk K and the head, and which extends upwardly around 5 the pipe J, and is adjustably suspended from the bearing D', and is driven through a gear E', which is preferably driven by a cone pulley F' and belt G' from a reverse cone pulley H' on the shaft h. By shifting the 10 belt the relative speeds of the pulleys F' and H' can be regulated.

In such an adaptation the blowers are carried by a head I', which has a tubular stem g', surrounding the tubular part of the head 15 B', and carrying a gear J' from which it is driven by a gear K' on the shaft h. The head I' is adjustably supported by a collar L' from a bearing M' at the top, and is steadied by a bearing N' at the bottom, the 20 latter bearing being disposed within a concavity in the head of the casing so as to bring the support as far as possible within the blower and thus aid in resisting any gyroscopic tendency of the latter.

25 All bearings consist of an annular cup i' receiving an annular flange j' so that the bearings run in oil. Each bearing is clamped in a half socket in the frame g so that by removing the clamps the parts can 30 be bodily removed sidewise, the parting faces of these clamps corresponding with the diametric parting of the casing, so that by removing a detachable half the interior is accessible.

35 The gears, bearings and collars, are inclosed for dust protection, and the upper bearing D' is formed on a frame m' removably carried on the frame g so that, when differential speeds between the distributor 40 and the blower are not desired, this frame may be removed and the bracket n', detachably carrying the feed tube and supporting the hopper, may be lowered onto the bearing M' of the frame. In such case the distributor and the blowers may both be carried by the same head.

45 For classifying or grading the fines my invention preferably provides one or more classifying chambers, between the dust chamber G and the return chamber H. One auxiliary settling chamber O' is shown, which is preferably concentric of and partly inclosed in the chamber G, and surrounds 50 and partly envelops the chamber E. The discharge from the chamber G slowly flows therefrom toward the inlet o' to the first classifying chamber, and is discharged downwardly in the latter through this contracted annular inlet, so that dust in the current 55 may be precipitated by its velocity and by centrifugal action, as well as by gravity, as the discharge expands within the large part of the chamber O' and the speed diminishes. The exhaust from the chamber 60 O' is slowly withdrawn through a large out-

let P' leading past a damper p' to the cone S and chamber E, or to the succeeding classifying chamber if several are used, where the operation is repeated as often as desired. From the last classifying chamber 70 the discharge is taken through the exhaust passage V and the return passage H and into the chamber E as before explained. Any desired number of these classifying chambers may be interposed between the discharge and the suction chambers and the fineness of product to be collected in each 75 may be determined by properly proportioning the chambers, or the current speeds, or the superficial area of the inlet and outlet. 80 A separate outlet spout may be provided for each chamber, or the various separations may be combined in one outlet, in which case the auxiliary chambers will simply be used as supplemental purifiers of the current returning to the separating chamber.

85 The return passage H constitutes a sinuous conduit between the fine chamber G and the distributing chamber E, and when one or more intermediate classifying chambers are interposed these are essentially a part of the return passage, and constitute enlargements or modifications thereof suited to effect the desired current modification best suited to the particular functions of each intermediate chamber. Making these intermediate chambers concentric and annular, and nesting them together between the tailings cone and the conical bottom of the separator attains great compactness, while permitting uniform annular current passages which facilitate uniformity of speed of flow 90 at all sides of any part of any passage or chamber. This uniformity throughout the effective part of any compartment or passage is a feature of my invention which is accomplished by extending cylindrically the termination of any conical member until the cylindrical extension has passed the termination of a conical portion of the next succeeding member, as illustrated in Figs. 2 and 100 3. This is done where height limits permit and the uniformity is essential. But in the construction shown in Fig. 1 this feature is 105 only partially utilized.

110 As thus far described the invention can be used as a current separator alone, but my invention provides for combined mechanical sizings as well as current sizings within the one machine, and this is preferably accomplished by one or more screens beneath the distributing chamber E, receiving the discharge from the return cone O, and grading and sizing it so as to separate out desired sizes before the remaining tailings or fines 115 passing these screens are permitted to fall onto the tailings cone S. Two sizing screens, a coarse inner one Q', and a medium outer one R' each conical and nested together, are shown as yieldingly suspended by springs S' 120 125 130

from the return cone O, so as to receive the tailings therefrom. The coarsest material flows down the screen Q' and falls through its outlet to the coarsest outlet q'. Material 5 passing through this screen flows down the screen R' and escapes through the medium outlet r', and material passing through the screen R' flows down the tailings cone S to the tailings outlet I. The outlets r', q' and 10 I are connected to their respective cones by a series of conduits or pipes s' passing each within the next, either concentrically as shown, or nested eccentrically so as to give the greatest external passageway at the 15 lower side if desired. In this manner three mechanical gradings are effected in addition to the current gradings.

To agitate the mechanical screens my invention provides a swinging knocker T' 20 which preferably revolves with the distributor and strikes a projection t' on the screen when the latter is depressed, these parts being normally out of coincidence, but being brought into the same path by the depression 25 of the screens either by reason of the weight of material on it if it becomes clogged, or by means of the handle k' when desired. To permit this depression the screens are yieldingly mounted by means of 30 their cylindrical necks l' in the upper ends of their respective pipes s'. Thus they will automatically cause themselves to depress the springs and to be agitated when overloaded, and restore themselves when free 35 from undue weight.

This invention provides an additional exhaust and a supplemental blast, which may be used in conjunction with or in substitution for the internal blower. I prefer to 40 provide a secondary external return passage U', communicating with the chamber G at the outlet of the passage U, and extending upwardly and discharging into a chamber u' from which a tangential exhaust V' leads 45 to and discharges tangentially into a centrifugal drum v' from which a suction pipe W' leads to a secondary or outer blower X'. The pipe W' draws downward from an inverted cup or dust apron w' in the drum v'. 50 An annular outlet x' withdraws dust settling in this drum.

The blower X' exhausts through the pipe Y' into a drum Z' located within the chamber E, having a tubular central blast outlet 55 y' therein and an internal equalizing cone z' to insure uniform distribution of the current within the drum.

The current may be increased or regulated by regulating the outside blower X', or by a 60 butterfly or other valve in either its blast or suction pipe, in addition to the regulation which can be obtained by the driving mechanism D or the dampers in the chamber E or those in the passage H. C' in Fig. 1 is 65 such a regulator.

In operation the material entering the feed pipe will be controlled by its adjustment, the speeds and currents will be regulated to give the desired results and the various products will be separately withdrawn according to classification. One or 70 all of the methods of classification will be used according to particular requirements.

When a single classification with an outside blower will suffice the modification 75 shown in Fig. 2 may be used, in which the tailings cone S is extended into and constitutes a continuation of the blast pipe Y' beyond which its outlet I discharges, and the passage H surrounds the cone S and its 80 outlet and constitutes a part of the suction pipe W', opening into the centrifugal drum v' which in this instance surrounds both pipes. In this view the improved scalper N is shown above the hopper C. This scalper 85 consists of parallel wires alternately of greater longitudinal extension at their lower ends which are bent at right angles and extended a sufficient distance before meeting the adjacent part of the chute which supports them, thus leaving an overhanging part of sufficient depth to clear any nail or other large piece which hangs through the scalper and extra room at its extremity for 90 its escape.

In the modification shown in Fig. 3 the same arrangement for outside blower as referred to in Fig. 2 is utilized in conjunction with an intermediate settling chamber X, the outlet of which surrounds the passage 100 H and is surrounded by the outlet j' of the chamber G.

When desired the feeder may be an inverted cone K'', within a distributor L'', which may consist of a ring k'' and a plurality of annular reverse oblique plates, Q'' and R'', which may be stationary, relatively adjustable, and approximately cylindrical in their relation, so that the blower F'' may extend past each without the necessity of flaring it, for example, as shown in Fig. 4. In this way the bearings may be brought farther within the blower, the cone of the distributor being relied on to lift the feed to the top of the annular distributors, and the fan being carried from the top of and driven by the cone.

A selector A'', as the spaced plates r'' between the rings s'' and blades p'', carried by or revolving with the blower, may be used in the current to give additional centrifugal action to the coarser pieces it carries and to throw these outwardly through the descending currents. An extractor B'', shown as a series of incline rings, may surround the chamber T for catching the coarser pieces, and a collecting chamber C'' may receive these and discharge them into an outer casing D''.

A blower E'', consisting of blades t'' and 130

ring u'' , carried and driven by the blower F'' , can be placed in the chamber G , and carry a cleaner J'' for throwing any floating particles through the extractor G'' , into the chamber H'' having an outlet I'' .

It will be understood that the invention is not limited to the particular details of construction, arrangement and combination set forth, as it can be employed in whole or 10 in part according to any modifications.

For the purpose of more completely disclosing the scope and practicability of the features incident to this invention which I prefer to claim in this application many features of improvement in separators and similar devices are herein shown and set forth but not specifically claimed in this application, being the subject matter of 15 claims in my applications Serial Nos. 858,797, filed August 27, 1914; 859,004, filed 20 August 28, 1914, and 859,145, filed August 29, 1914.

What I claim is:

1. In separators and similar devices the 25 combination with a casing, means for feeding material thereto, and means for creating a current therein through such material, of means subdividing such material in its distribution within such casing, and surrounding means subdividing such current between the subdivisions of such distribution into superposed approximately horizontally outwardly flowing strata.

2. In separators and similar devices, the 35 combination with a plurality of distributor for material to be separated, of isolated surrounding means for causing a current to traverse such material between each distributor independently of the others and approximately horizontally outwardly therefrom.

3. In separators and similar devices, the combination with a plurality of distributor for material to be separated, of isolated 45 means for creating a current through such material opposite each distributor independently of any current opposite other distributor.

4. In separators and similar devices, the combination with a plurality of distributor for material to be separated, of an independent blower surrounding each distributor.

5. In separators and similar devices, the combination with a plurality of distributor for material to be separated, of a suction 55 blower surrounding each distributor.

6. In separators and similar devices, the combination with a plurality of distributor

for material to be separated, and blowers surrounding them, of isolated exhaust chambers for each distributor and a common exhaust passage for said blowers.

7. In separators and similar devices, the combination with a plurality of distributor for material to be separated, and a blower surrounding said distributor, of an annular 65 exhaust passage surrounding said distributor, a reverse return passage inwardly of said exhaust passage, and a settling chamber communicating the said passages.

8. In separators and similar devices, a revolving distributor and a revolving blower surrounding it, in combination with means for differentially driving said parts, and means for adjusting their relative speeds.

9. In separators and similar devices, a 75 casing, means for distributing material therein, means for causing a current to traverse the distributed material, a rotary blower within said casing below and surrounding said distributor for causing an outward current within the apron of distributed material, and means for returning such current to such blower.

10. In separators and similar devices, a 85 casing, means for distributing material therein, means for causing a current to traverse such material and a damper beneath and inwardly of said distributor for regulating such current inwardly of the apron of distributed material.

11. In combination, means causing a current to traverse material, a conical screen receiving such material, means for moving said screen axially.

12. In separators and the like, a casing, 95 means for distributing material therein, and means for causing a current to flow outwardly through said material, in combination with an annular centrifugal selector surrounding said distributing means.

13. In separators and the like, a casing, means for distributing material therein, a settling chamber, and passages leading to and from the latter, in combination with an annular extractor surrounding the passage 105 leading from said chamber.

In witness whereof, I have hereunto signed my name in the presence of two subscribing witnesses.

GEORGE HOLT FRASER.

Witnesses:

FRED WHITE,
THOMAS F. WALLACE.
